UNITED STATES PATENT OFFICE.

BENJAMIN SCHWARTZMAN, OF NEW YORK, N. Y., ASSIGNOR TO SAMUEL SHAPIRO, JOSEPH SHAPIRO, SOLOMON SHAPIRO, DAVE SHAPIRO, AND MORRIS BERMAN, ALL OF NEW YORK, N. Y., COPARTNERS DOING BUSINESS UNDER THE NAME OF RELIANCE METAL SPINNING COMPANY, OF NEW YORK, N. Y.

DESIGN FOR A SHOWER-PLATE FOR GAS AND ELECTRIC FIXTURES.

49,162.

Specification for Design.

Patented June 6, 1916.

Application filed January 12, 1916. Serial No. 71,795. Term of patent 7 years.

To all whom it may concern:

Be it known that I, BENJAMIN SCHWARTZMAN, a citizen of the United States, residing at the city of New York, borough of Brooklyn, in the county of Kings and State of New York, have invented a new, original, and ornamental Design for a Shower-Plate for Gas and Electric Fixtures, of which the following is a specification, reference being had to the accompanying drawing, forming part thereof.

Figure 1 is a plan view of a shower plate for gas and electric fixtures, showing my new design. Fig. 2 is an edge view of the design shown in Fig. 1.

I claim:

The ornamental design for a shower plate for gas and electric fixtures, as shown.

BENJAMIN SCHWARTZMAN.
